UNITED STATES PATENT OFFICE

WALTER E. DISNEY, OF HOLLYWOOD, CALIFORNIA

DESIGN FOR A TOY FIGURE

Application filed March 30, 1931. Serial No. 39,302. Term of patent 14 years.

To all whom it may concern:

Be it known that I, WALTER E. DISNEY, a citizen of the United States, residing at Hollywood, in the county of Los Angeles and State of California, have invented a new, original, and ornamental Design for a Toy Figure, of which the following is a specification, reference being had to the accompanying drawing, forming part thereof.

In said drawing

I claim:

The ornamental design for a toy figure, as shown.

WALTER E. DISNEY.
